STOVE LID LIFTER

Samuel Klute, South Bend, Ind., assignor to The
Malleable Steel Range Manufacturing Co.,
South Bend, Ind.

Application March 28, 1934, Serial No. 717,792

4 Claims. (Cl. 126—211)

The invention relates to stove lid lifters, and more particularly to means for lifting, as a unit, the anchor plate and lids carried thereby which cover the fire chamber of a wood or coal burning cooking stove or range, to facilitate and simplify the operation of supplying fuel to such fire chamber.

The primary object of the invention is to provide lifting mechanism of this character which is normally in an out-of-the-way position and practically concealed.

A further object is to provide lifting mechanism of this character which raises the stove lid in a pivotal movement without inoperatively shifting the pivot end of said lid.

A further object is to provide lifting mechanism of this character including a pivoted member normally depending freely but extensible for engagement with a stop to support the mechanism and lid in raised or pivoted position.

A further object is to provide lifting mechanism of this character positioned rearwardly of the stove and carried by an extension of the stove lid for movement through an opening in the top frame of the stove.

A further object is to provide lifting mechanism of this character utilizing a curved arm depending from the stove lid for lifting one end of said lid in an arcuate path and thereby pivoting said lid.

With the above and other objects in view, the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a perspective view of a stove to which my improved lifting mechanism is applied.

Figure 2 is a fragmentary perspective view of a stove illustrating the lid supported and locked in raised position by the lifting mechanism.

Figure 3 is a fragmentary view of a stove in rear elevation illustrating the lifting mechanism.

Figure 4 is a fragmentary view in side elevation illustrating the support for holding the lifting mechanism in raised position.

Figure 5 is a side view of the lifting mechanism illustrating part of the stove in a section taken on line 5—5 of Figure 1.

Figure 6 is a fragmentary sectional view of the stove taken on line 6—6 of Figure 1.

Referring to the drawings, which illustrate the preferred embodiment of the invention, the numeral 10 designates a wood or coal burning cooking stove having a base 11, front panel 12, side panels 13, rear panel 14, top frame 15, and an upwardly extending back guard 16. The top frame 15 carries lid 17 for the reservoir, cooking plate 18, and anchor plate 19 covering the fire chamber; said anchor plate 19 carrying round lids 20 and intermediate lid 21, all as is conventional.

An extension 22 is carried by anchor plate 19 at an intermediate portion of the rear side thereof, and this extension 22 fits into an opening 23 in top frame 15, which opening 23 extends rearwardly of the rear panel 14 of the stove cabinet. A downwardly extending flange 24 is integrally formed with extension 22 and projects through said opening 23. At the opposite ends of its inner side portion, anchor plate 19 has integrally formed therewith downwardly extending fingers 25, and these fingers fit into recesses 26 formed in the top frame 15, and are notched at 40.

A curved arm 27 is riveted or otherwise fixedly secured to flange 24 of anchor plate extension 22, and extends downwardly therefrom in closely spaced parallel relation to rear panel 14 of the stove. The major portion of arm 27 is substantially arcuate whereby its center line substantially conforms to an arc having a point on a line common to fingers 25 as a center; and its lower free end portion 28 is preferably straight and extends at an angle to the horizontal, as a tangent to said arc at that point. To portion 28 of arm 27 is riveted or otherwise fixedly secured, at the outer side thereof, the end of a second arm 29. Arm 29 is provided with a perpendicularly rearwardly bent portion 30, from which the free end 31 of said arm extends in parallel relation to portion 28 of arm 27 and to rear panel 14 in rearwardly spaced relation to a vertical projection of the rear edges of the top frame 15 and back guard 16. The outer end of portion 31 of arm 29 is curved at 32 and terminates in a bifurcated portion 33 positioned adjacent to a rearward projection of the adjacent side panel 13 of the stove. A handle member 34 is pivoted at 35 to portion 33, and normally depends vertically therefrom, as illustrated in Figure 3.

The back guard 16 of the stove includes a vertical member 36, as best illustrated in Figure 4, and the rear edge of said member carries a plurality of rearwardly projecting upwardly di-

rected fingers 37, opposite which fingers said member is cut away at 38.

In the use of the device, handle 34 is pivoted to extended position, as illustrated in dotted lines 5 in Figure 3, there being provided therefor suitable means (not shown) for limiting such pivotal movement to desired extended position. An upward pull on the handle then raises the mechanism and anchor plate 19. The fingers 25 of this 10 anchor plate, being seated in recess 26 of frame 15, serve to form a pivot bearing for the plate, whereby said plate is pivoted, and any tendency to move laterally or of said fingers to slide from said recess is overcome by engagement of notch 15 40 with the recess corner, as shown in Fig. 6. The curvature or arcuate form of the arm 27 is such that, as the lifting mechanism is raised, it will move freely through opening 23 in frame 15, and that it will continually urge the plate 19 in a 20 direction tangential to its path of movement or perpendicularly thereto; which serves additionally to insure movement thereof will be limited to pivoting. The off-set relation of the major free portion 31 of arm 29 with respect to arm 27 and 25 the rear edges of the frame 15 and back guard 16, permit the same to be raised to a position as illustrated in dotted lines in Figures 3 and 5, whereby plate 19 is pivoted sufficiently to permit large pieces of wood to be placed in the fire chamber. In this connection it will be seen that the 30 positioning of the arm 27 outwardly of a projection of the rear edge of plate 19 provides an uninterrupted passage in frame 15 through which the fuel may be fed to the fire chamber. The 35 perpendicular portion 30 of arm 29 provides a stop which engages frame 15 if the mechanism is lifted too high, and this portion 30 is positioned, with relation to the pivot edge of plate 19, at an angle to the vertical, whereby the plate 19 can- 40 not be pivoted to or beyond vertical position, and consequently the lids 20 and 21 will not fall or move from operative position on said plate. To lock or support the plate 19 in raised position, the handle 34 is disposed in one of the recesses 45 38 of member 36 to be supported by the adjacent finger 37, the handle thus being normally suspended adjacent the lateral outline of the stove but being extensible outwardly thereof to engage the supporting fingers 37 and to serve therewith 50 to form a locking means for the plate 19. The extension 22 of plate 19, when said plate is operatively positioned on the frame, not only permits the lifting mechanism to be disposed behind the stove cabinet in practically concealed position, 55 but also serves to close opening 23 of frame 15 in which the lifting mechanism is shiftable, thereby concealing said opening and enhancing the appearance of the stove.

The invention having been set forth, what is 60 claimed as new and useful is:—

1. The combination with a stove comprising a cabinet, a top frame for said cabinet projecting outwardly of one side thereof and having a plate receiving opening therein, a plate pivotally 65 mounted on said top to cover said opening, of a

depending curved arm fixed to said plate in spaced relation to the pivot axis thereof and disposed below said top projection in spaced relation to said cabinet and a handle fixed to the free end of said arm and outwardly off-set therefrom whereby the free end of said handle is shiftable in a vertical path of movement spaced from said top projection to a position thereabove to pivot said plate by shifting said arm in said opening to a limit at which said off-set engages said top 10 projection. 5

2. The combination with a stove comprising a cabinet and an upper structure, a top for said cabinet projecting outwardly thereof, having a plate receiving opening therein, a plate pivotally 15 mounted on said top to cover said opening, of a depending curved arm fixed to said plate in spaced relation to the pivot axis thereof and disposed below said top projection in spaced relation to said cabinet, a handle fixed to the free end of said arm and outwardly off-set therefrom whereby the free end of said handle is shiftable in a vertical path of movement spaced from said top projection to a position adjacent said upper structure to pivot said plate by shifting said arm in 20 said opening to a limit at which said off-set engages said top projection, and means carried by said upper structure and engageable by said handle for supporting said handle in raised position. 30

3. The combination with a stove comprising a cabinet and an upper structure, a top for said cabinet projecting rearwardly thereof, and having a plate receiving opening therein, a plate pivotally mounted on said top to cover said opening, of a depending curved arm fixed to said plate in spaced relation to the pivot axis thereof and disposed below said top projection in rearwardly spaced parallel relation to said cabinet, an extensible handle carried by the free end of 40 said arm and normally concealed rearwardly of said cabinet, said handle including a rearward projection whereby the free end thereof is shiftable in a vertical path of movement spaced from said top projection to a position adjacent said 45 upper structure to pivot said plate to a limit at which said off-set engages said top projection, and means carried by said upper structure and engageable by said handle when extended for supporting said handle in raised position. 50

4. A stove comprising a frame having a lid receiving opening therein, a pivotable lid, a lid supporting flange carried by said frame and having an elongated recess formed therein defined at one end by a shoulder, and a depending pivot bearing carried by said lid mounted in said recess and longitudinally shiftable therein upon pivoting of said lid, said bearing having an inclined face slidable on said shoulder and interrupted by a notch intermediate thereof, said notch seating on said shoulder after a predetermined shifting of said bearing relative to said shoulder to prevent sliding displacement of said bearing from said recess during pivoting of said lid. 60
